UNITED STATES PATENT OFFICE.

FREDRICK G. SCHNEIDER AND WILLIAM C. L. ZIEHN, OF CHICAGO, ILLINOIS.

BEVERAGE COOLING AND DISPENSING APPARATUS.

No. 902,333.

Specification of Letters Patent.

Patented Oct. 27, 1908.

Application filed October 29, 1907. Serial No. 399,780.

To all whom it may concern:

Be it known that we, FREDRICK G. SCHNEIDER and WILLIAM C. L. ZIEHN, citizens of the United States, residing at Chicago, in the county of Cook and State of Illinois, have invented certain new and useful Improvements in Beverage Cooling and Dispensing Apparatus, of which the following is a specification.

This invention relates essentially to improvements in work boards used generally in connection with bars and soda fountains; and has for its objects, to construct the apparatus in such manner that it will be absolutely sanitary at all times; to construct the rinsing tanks and bottle cooling tanks entirely of metal, and to employ round corners in the same so as to prevent sediment and impurities from lodging therein; to make the structure in sections which, when set up, will form one homogeneous structure, thereby adapting the apparatus for ready use, in large or small places, as required; to provide a perfect drainage system, which will not only keep the apparatus in proper sanitary condition but will, moreover, in a large measure, if not entirely, dispense with the use of ice as a cooling medium, which is a feature of prime importance in a device of this character; and the invention finally consists in the features of construction and combination of parts hereinafter described and claimed.

In the drawings, Figure 1 is a side elevation of the improved sanitary work board set up for use; Fig. 2 a top or plan view thereof; Fig. 3 a vertical sectional view showing the arrangement of the glass liquid receptacle and the supports therefor; Fig. 4 a top or plan view of the cap of the liquid receptacle; Fig. 5 a transverse section taken on line 5—5 of Fig. 3; Fig. 6 a vertical sectional elevation illustrating the manner in which the water is admitted to the system, as well as the induction pipe or tube adapted to convey the liquid from the casks or barrels (not shown) in connection therewith; Fig. 7 a longitudinal sectional view of the structure; Fig. 8 a detail in section of the liquid cooler; Fig. 9 a cross section taken on line 9—9 of Fig. 7; and Fig. 10 a similar view taken on line 10—10 of Fig. 7.

In constructing this sanitary work board, we prefer to make the bottle cooling receptacle 11 and the rinsing tank 12, respectively, of any suitable metal or material which will

not leak and which is capable of retaining a perfect enameled surface so as to especially adapt itself for the work intended. Drain openings 11' are formed, as usual, in the bottoms of the cooling receptacle and tank, and an overflow 12^a is located near the upper outer edge of the rinsing tank. Positioned slightly above the rinsing tank and on its farther side is a faucet 12^b for supplying water to the rinsing tank. The aforesaid receptacles are made integral, respectively, and have all their corners rounded so as to prevent sediment or impurities from lodging therein, it being one of our primary objects to make the structure sanitary in every respect.

We prefer to make the sanitary work board in sections, thus enabling the same to be easily transported and set up in large or small places, as desired. Accordingly, the joints 13 of the various sections are made with special reference to fitting together where they are firmly cemented in position in the usual manner; and, as shown, bolts 14 are adapted to be passed through and secured to lugs 15, formed on the parts adjacent to one another, for securing the respective sections in proper position. Longitudinal supporting beams 16 are secured, at their ends, to transversely disposed end channel bars 16', by bolts 17. Bosses 18, having interior screw threads, are screwed to the aforesaid beams and are adapted to receive the upper threaded ends of the supporting legs 19, said legs being first set in feet 20, which are firmly secured to the floor. Holes 19' are formed in the body of the supporting legs and are adapted to receive rods (not shown) which, when put therein, form suitable levers with which to secure the legs in proper position. Another feature of importance arising from the use of this construction is the fact that the structure can always be positioned with facility when the floor sags and becomes uneven. Where space permits, an auxiliary end board 21 may be utilized if desired, the same being supported by diagonally disposed braces 22 secured to the structure.

Adjacent to and connected with the rinsing tank 12, in the same manner as the sections heretofore described, is a horizontally disposed tray 23, of the usual character, adapted to receive glasses after the same have been cleaned in the rinsing tank, said tray comprising a plurality of spaced cross rods or bars 24, retained in fixed position by

outer and intermediate metallic strips 25, the tray as a whole being made of copper or other suitable material. This tray is adapted to be positioned slightly above the inclined drain plate 26, which is secured to the rinsing tank 12, as shown, and receives the liquid dripping from the aforesaid tray upon which the glasses are placed for drying, and permits said liquid to flow off into a sink. 5 Along the inner side of the tray 23, rinsing tank 12, and bottle cooling receptacle 11, is formed an upright shield 23', about two inches in height, which serves to prevent the water from splashing on the dress of the attendant. 10

The cooler 30 is supported, as usual, upon legs adapted to be set in feet at the lower ends, and to have their upper threaded ends retained in bosses, as heretofore described. 20 A plurality of depending metal pipes 31 are adapted to extend downwardly through the floor 32 of the building, to directly communicate with the beer kegs or other liquid receptacles. In order to enable a perfect 25 drainage system to be used in connection therewith, I prefer to use glass liquid conveying tubes or pipes 33, which are positioned centrally within the aforesaid depending metal pipes 31. As there is considerable 30 space about the glass liquid conveying tubes 33 within the metal pipes 31, as indicated in Figs. 3 and 4, water under pressure, when admitted from the water cock 34, will be forced upwardly therefrom. When more 35 than one keg or receptacle is tapped, the apparatus may be duplicated, as desired, it only being necessary that a common water supply pipe 35 be used to convey the water to the respective depending metallic pipes 40 31. A drain cock 36 is located opposite the water supply cock 34, thus affording means for draining out the system when necessary.

The water supply cock 34 is secured to a four-way coupling 34' of the usual type, 45 which permits the admitted water to be forced upwardly by pressure through the pipes 31. Plugs 37 are screwed into the lower passage of these couplings 34', and packing boxes 38 are secured therein. 50 Glands 39 are positioned below and in alignment with the aforesaid stuffing boxes and are fixedly retained by caps 40, which have nipples 41 depending therefrom, adapted to receive the upper ends of hose 42, which connect with the kegs or other liquid tanks. 55 Above the floor 32 of the building is a plate 43, having three lugs formed thereon, adapted to be secured by suitable fastening means to the bottom of the cooler. A stuffing box 60 44', as usual, is secured below the inlet of the liquid receptacle.

The glass liquid retaining vessel 44 is in direct communication, as shown, with the glass tubes, which are inclosed in the metal

pipes 31, and has an outlet 45 at its upper 65 end. An upper cross head 46 is adapted to be positioned over the threaded ends of the tie rods 47, which are suitably secured at the bottom, the same being retained in place by wing nuts 48. Adjacent to the retaining 70 vessel 44, in the cooler 30, is a space 49, within which ice may be stored when desired, although it is not necessary. Should ice be placed therein, a wire screen is put between the liquid receptacles and the ice to 75 prevent damage thereto. The beer or other liquid contained in the glass vessel or receptacle 44, passes out through the outlet port or passage 45 into a draft tube, from which it is then ready to be drawn from the 80 faucets 50 for drinking purposes. A suitable sink 51 having a drain 53, is secured beneath the faucets on the cooler to catch the waste. The water surrounding the retaining vessel 44 is permitted to escape into 85 a cup secured to the side of the cooler aforesaid, which enables the same to thence flow through a downwardly slanting pipe 52, which deposits the water into the rinsing tank, where it escapes through the overflow 90 passage 12^a. It is understood, of course, that there are as many metal pipes 31 as there are liquid retaining vessels 44, and that a common water supply pipe and drain cock 95 will be sufficient for the entire system, regardless of the number of tubes employed.

In operation, the water will be admitted through the water supply cock 34, and the pressure thereof will cause the same to rise within the metal pipes 31 surrounding the 100 glass liquid conveying tubes 33, until the water ascends to a point adjacent the top of the liquid retaining vessel 44, when it is permitted to overflow through the drain, where it is caught and permitted to flow downwardly therefrom through the conducting pipe into the rinsing tank aforesaid, and from which it is permitted to escape through the overflow 12^a.

From the foregoing it will be seen that an 110 even and regular temperature will be practically maintained at all times—the water being constantly forced through the pipes adjacent the liquid conveying tubes. It is obvious that when the foregoing water system is employed for the aforesaid purposes the liquid affected thereby will at all times be at an even temperature regardless of weather conditions or extraneous influences; and that in a large measure, if not entirely, 115 this apparatus does away with the use of ice, which is an item of considerable expense in this particular business. Another matter of importance is the fact that the device is made in sections which permit the ready assembling of the same, so that it is equally as serviceable in large as in small places. All of the parts are constructed with reference to being 120 125

readily accessible for cleaning purposes; and, in view of the fact that there is a constant stream of water flowing through the system, the natural tendency is to cleanse every-
 5 thing, and especially the rinsing tank in which the glasses are being constantly dipped and rinsed. The metallic bottle cooling receptacle and rinsing tank, being made of suitable metal and properly enameled, will
 10 be non-leakable and at the same time will present a highly finished appearance; and, as all corners are rounded, it will be impossible for impurities to lodge therein. The use of glass liquid conducting tubes, in conjunction
 15 with the glass liquid retainers, tends to make the device sanitary in its essential features. No metal pipes or tubes come into contact with the particular liquid acted upon, so that the apparatus guards against impurities con-
 20 taminating the liquid and thereby deteriorating the same. The entire device, from the details thereof to its most important features, is constructed with a view to making the same absolutely sanitary as well as efficient
 25 and perfect in operation.

What we claim as new and desire to secure by Letters Patent is:

1. A receptacle for liquid made of sanitary material and open at both ends, a cap having
 30 an annular rim entered into the open end of the receptacle, a packing between the cap and the end of the receptacle, a discharge passage through the cap and rim, a support-
 35 ing plate having a rim entered into the open end of the receptacle, a packing between the plate and the end of the receptacle, a sup-
 porting plate carrying the plate with the rim, and tie rods between the cap and the sup-

porting plate for sealing the receptacle at each end, substantially as described.

2. In combination with a beverage cooling and dispensing apparatus, a liquid cooler having a beverage receptacle therein, a de-
 40 pending metallic pipe attached to the liquid cooler, a longitudinally disposed glass liquid 45 conveying tube within the metallic pipe in communication with a keg or tank and the beverage receptacle, means for drawing off the liquid from the beverage receptacle, a wa-
 ter supply valve opening into the aforesaid 50 depending metallic pipe for permitting wa-
 ter to flow within the metallic pipe about the liquid conveying tube, and means for carry-
 ing off the water, substantially as described.

3. In combination with a beverage cooling and dispensing apparatus, a liquid cooler having a beverage receptacle therein, a me-
 55 tallic pipe depending therefrom, a longitudi-
 nally disposed glass beverage conveying tube in direct communication with a keg or tank 60 and the beverage receptacle, means for drawing off the beverage from the beverage receptacle, a water supply pipe opening into the aforesaid depending metallic pipe for per-
 65 mitting water to flow within the metallic pipe about the beverage conveying tube and the beverage receptacle, a rinsing tank, and means for permitting the water to drain off and be conducted to a rinsing tank, substan-
 tially as described.
